UNITED STATES PATENT OFFICE.

WILLIAM LEWIS EVANS, JR., OF WASHINGTON, INDIANA.

HINGE.

Application filed May 12, 1923. Serial No. 638,596.

To all whom it may concern:

Be it known that I, WILLIAM L. EVANS Jr., a citizen of the United States, residing at Washington, in the county of Daviess and State of Indiana, have invented new and useful Improvements in Hinges, of which the following is a specification.

This invention relates to hinges of the multiple pivot type, in which a door plate 10 and a pair of floor or ceiling plates are combined with a pair of swinging arms, the opposite ends of which are pivoted respectively to said plates in such relation to each other that they will always assume a non-parallel 15 position.

The present invention is an improvement 20 on the hinges shown, described and claimed in my prior Patents No. 1,367,954 and No. 1,407,790, dated respectively February 8th, 1921, and February 28th, 1922.

In the hinge of the first patent, the elements of the hinge are not permanently connected together at the factory, but are constructed so as to be shipped in knock-down 25 form and assembled on the job. When applying the hinges to the door, it is necessary to properly space the arms, and this requires considerable care and experience in order that when the hinge is fastened to the door, 30 the terminals of the arms will stand vertical; otherwise when swinging the arms they would bind and make the door hard to operate even to the extent of loosening the plates which have been secured to the door. Moreover, in this construction, wherein hinges 35 are located at the top and bottom, the load is entirely carried by the arms of the bottom hinge and this, to a certain extent, limits the application of the hinge to light structures.

In the later Patent 1,407,790, certain of the defects of the hinge of the first-mentioned patent were avoided by making the hinge in entirely assembled form at the factory, and also constructing the hinge so that 45 the load should be divided between the top and bottom hinges of the door.

The extensive manufacture and sale of these hinges has made it necessary to develop a further improvement which is presented 50 by the structure of the present application, consisting of an improved connection between the terminals of the arms and the floor and ceiling plates, and also by constructing the door plate of a greater length than the 55 length of the arms, this construction being

of advantage not only in shipping the completed hinge, but when applying the hinge in position.

Also by this construction, a hinge is provided which will support a load twice as 60 heavy as if the load were only supported from the bottom hinge; moreover the parts of the hinge are permanently connected and assembled precluding the loss or misplacement of any of the parts; and finally the hinge is much easier to install on the door, and can be put in place by an ordinarily skilled person, for when the door plate is placed horizontally on the door, the terminals of the arms automatically assume a vertical 65 position in proper relation with the door.

The invention will be best understood 70 from a consideration of the following detailed description, taken in connection with the accompanying drawings forming part 75 of this specification, with the understanding that the invention is not limited to a particular or exact form as represented in the drawing, but may be changed and modified 80 so long as such changes and modifications mark no material departure from the salient features of the invention, as expressed in the appended claims.

In the drawings:

Figure 1 is an inside view of a door with the top and bottom hinges applied in position;

Figure 2 is a horizontal section of the same 90 showing in full lines the door in its closed position and in dotted lines the movement of the door from closed to open position;

Figure 3 is an elevation with parts in section disclosing the upper hinge;

Figure 4 is an elevation with parts in section disclosing the lower hinge;

Figure 5 is a transverse section showing the connection between the terminal of one of the arms and the floor or ceiling plate;

Figure 6 is a horizontal section on the line 100 6-6 of Figure 5;

Figure 7 is a detail perspective view of the collar which is employed in connection with the floor or ceiling plate.

Like reference characters designate corresponding parts in the several figures of the drawing.

While the hinge is capable of use for swingably mounting any movable member, as for instance, a door or window, I shall 110

describe the invention as applied to a door, with the understanding that the invention is not to be limited by such description.

The door or other movable member is provided with an upper hinge and a lower hinge, each hinge consisting of a pair of arms, a door plate, and a pair of floor or ceiling plates. As the upper and lower hinges differ from each other only in the length of the terminals of the swinging arms, it is deemed unnecessary to describe both hinges, as a description of one hinge will apply to the other.

Each hinge has a pair of swinging arms 10 and 11 of approximately the same length and they are constructed like the arms of my prior patented hinges. Each arm has an upturned and downturned terminal marked respectively 10^a, 10^b, 11^a, 11^b. The upturned terminals 10^a, 11^a, of the arms of the lower hinge are longer than the downturned terminals 10^b, 11^b of the arms of the same hinge, while the terminals of the arms of the upper hinge are longer than the corresponding terminals of the arms of the lower hinge.

The door plate 12 is made of flat metal and is secured to the inner face of the door by screws or bolts at a point between the opposite side edges. The opposite ends of the plate are notched or cut out at a point between the top and bottom, and the metal above and below each of the notches is coiled into knuckles 12^a, which are vertically aligned and spaced from each other by the said notches. Mounted in each notch or space is a collar 12^b, which is fastened to the upturned terminals 10^a, 11^a, by a rivet, or by spot-welding. By this construction, the collars turn with the upturned ends of the arms, which in turn move in the knuckles as the arms are swung to and fro.

The downturned ends 10^b and 11^b of the arms are secured to the floor plates 13 in the manner shown in Figs. 3, 4, 5 and 6 of the drawings. The floor plates are formed with centrally disposed bosses provided with openings to pass the downturned ends of the arms, and are counterbored to form a recess or pocket to receive a collar 14, which is riveted or spot-welded to the extremity of the terminal.

Above the floor plate, is another collar 15, which is riveted or spot-welded to the terminal. By this construction, the two collars are caused to move with the terminal of the arm, the collar 14 turning within the recess of the floor plate, while the collar 15 turns on the outside of the boss of the floor plate, the two collars supporting the load carried by the arms.

In applying the hinges to doors, the door should be set in its closed position and secured temporarily. The door plate should be placed horizontally on the door, with the end of the plate about nine inches from the

edge of the door, assuming that the arms are seven inches long, the floor or ceiling plates just touching the floor or ceiling, as the case may be, and the door plate then secured in this position. Next, shift the floor and ceiling plates along the floor or ceiling so that a line passing through the center of each plate shall extend at a right angle to the door opening, and screw the plates in position. Repeat this at the top for the upper hinge and the door will be properly hung.

An important feature of this hinge is the length of the door plate which exceeds the length of either of the arms. This is necessary in order to avoid clashing between the arms, which in this construction, work in the same horizontal plane.

Referring to Figure 2 of the drawings, wherein the door or movable member is shown in a closed as well as an open position, and the movement from the closed to the open position is indicated in dotted lines, it will be noted that the floor plates are located in a straight line at different distances from the opening or entrance to the compartment, and that said line is at right angles to said entrance or opening or to the door when closing the latter.

It will also be noted that in the closed position of the door, one of the arms is at a slight angle to the door, while the other arm is at an angle greater than a right angle and that the arms in their progressive movement never assume a parallel position to each other. As a result, the arms never clash with or touch each other, though they swing in the same horizontal plane. When the door is swung to its completely open position, the two arms are at an angle to each other, and thus hold the door firmly in its open position without the use of any fastening means.

By reason of the mounting of the ends of the arms in the floor door plate and floor and ceiling plates, each arm carries its share of the load, and this arrangement enables the arms of the upper hinge to assist the arms of the lower hinge in sustaining the weight of the door.

The hinge of the present invention is capable of all the uses of the hinges of the aforesaid patents, being adapted to be applied to the doors of closets, screen partitions, wardrobes, garages, coal chutes, or to the sashes of windows, ventilators or to any movable part or member which is designed to close either a compartment, space or room, where it is desired that the movable member shall vanish within the compartment when open. The hinges are all made alike and are capable of being applied for either right hand or left hand use.

What is claimed is:—

1. In a hinge, the combination of a plate

adapted to be secured to a floor or ceiling and provided with a recess or pocket, and an opening leading thereto, with an arm having a bent terminal passed through said opening into said recess or pocket, a collar rigidly fitted on said terminal within said recess or pocket, and a second collar also fitted on said terminal outside said plate.

2. In a hinge, the combination with a plate adapted to be secured to a floor or ceiling and provided with a boss forming a recess or pocket and an opening leading therefrom, of an arm having a bent terminal passed through said opening into said pocket or recess, and a pair of rigidly fastened collars spaced on said terminal, one collar being arranged in said pocket or recess and the other bearing on the outside of said boss.

3. A hinge comprising a pair of arms of substantially equal length, and means for pivoting the arms at opposite ends to a stationary and a movable member, consisting of a plate having its ends pivotally connected to and joining the ends of individual arms, and separate plates pivotally connected to the other ends of said arms, the first-mentioned plate having a length greater than the length of either arm.

4. The combination with a stationary member and a movable member, of means for pivotally connecting the movable member to the stationary member, comprising an upper hinge and a lower hinge, each hinge consisting of a pair of swinging arms having outturned terminals, a plate fastened to the movable member and having a length

greater than the length of either arm, and a pair of plates each fastened to the stationary member in spaced-apart relation, the outturned terminals of the arms being pivotally connected to the ends of the first-mentioned plate and to each of the pair of plates.

5. The combination with a stationary member and a movable member, of means for pivotally connecting the movable member to the stationary member comprising an upper hinge and a lower hinge, each hinge consisting of a pair of spaced arms having outturned straight terminals extending in different directions, a single plate fastened to the movable member and connecting one of the terminals of each of the pair of arms, and separate plates secured in spaced-apart relation to the stationary member and connected individually to the other terminals of said arms, the plate fastened to the movable member having at each end a pair of spaced aligned eyes receiving the terminals of said arms, and a collar rigidly mounted on each terminal in the space between the eyes, and the separate plates fastened to the stationary member each having a recess to receive a collar mounted on the terminal of the arm and a collar mounted on the same terminal and bearing upon the outside of said plates.

In testimony, that I claim the foregoing as my own, I have hereto affixed my signature.

WILLIAM LEWIS EVANS, JR.
